UNITED STATES PATENT OFFICE.

ERNEST M. PRESSLEY, OF KANSAS CITY, MISSOURI.

DESIGN FOR AN INDIVIDUAL COFFEE MAKER.

Application filed July 27, 1922. Serial No. 3,215. Term of patent 14 years.

To all whom it may concern:

Be it known that I, ERNEST M. PRESSLEY, a citizen of the United States, residing at Kansas City, Jackson County, Missouri, have invented a new, original, and ornamental Design for an Individual Coffee Maker, of which the following is a specification, reference being had to the accompanying drawing, forming a part thereof.

In the drawing—

The figure represents a perspective view of the device embodying my design.

I claim:

The ornamental design for an individual coffee maker, as shown.

ERNEST M. PRESSLEY.
